HEATING SYSTEM

Carl Georg Munters and Martin Hedmark,
Stockholm, SwedenApplication July 6, 1938, Serial No. 217,698
In Sweden July 17, 1937

9 Claims. (Cl. 237—55)

Our invention relates to heating systems for buildings, and more particularly to an improved flue or chimney forming part of such heating systems.

Heretofore it has been the practice to construct the flue or chimney of massive masonry. The thick walls of the chimney were necessary in order to provide sufficient heat insulation and the chimney necessarily had a large heat accumulating capacity, and the heat absorbed was lost to a great extent.

In accordance with our invention the flue is constructed of a number of metallic pipe sections of convenient length. Each section is surrounded by a water jacket in the form of a shell welded or otherwise suitably secured to the section or conduit forming the flue. Jackets on adjacent sections are connected together by means of one or more pipes which are preferably made of flexible material such as copper, to thereby permit a slight relative movement which results from expansion and contraction due to temperature changes. The water heated in these jackets may be utilized to heat the building and thus, in accordance with our invention, not only is the size of the chimney reduced, but the heat absorbed thereby is utilized.

A further advantage of our invention is that the flue may be installed after the building has been erected.

Further objects and advantages of our invention will be apparent from the following description considered in connection with the accompanying drawings which form a part of this specification and of which:

Fig. 1 is a cross-sectional view of one embodiment of our invention;

Figs. 2, 3 and 4 are cross-sectional views on a larger scale showing portions of the device illustrated in Fig. 1;

Fig. 5 is a cross-sectional view of another embodiment of our invention and is taken on the line 5—5 of Fig. 6;

Fig. 6 is a cross-sectional view taken on the line 6—6 of Fig. 5;

Fig. 7 is a cross-sectional view on an enlarged scale of a portion of the device shown in Fig. 6;

Fig. 8 is a cross-sectional view taken on the line 8—8 of Fig. 7;

Fig. 9 is a cross-sectional view taken on the line 9—9 of Fig. 6.

Referring more particularly to Figs. 1 through 4, reference character 10 designates generally a building having a cellar 11, a first story 12, a second story 13 and an attic 14 covered by a

roof 15. Located in the cellar 11 is a furnace, designated generally by reference character 16. Furnace 16 includes an inner shell 17 defining a combustion chamber and an outer shell 18 forming a water jacket around the furnace. A conduit 19 communicates with the combustion chamber and extends through the water jacket to the exterior of the shell 18.

Connected together and to the conduit 19 is a plurality of flue sections designated generally by reference characters 20 and 20a. Each of these sections includes an inner conduit 21 to which is secured a jacket 22. The ends of the conduits 21 extend beyond the jackets 22 in order to provide means for coupling the adjacent sections together. Section 20a differs from the sections 20 in that the jacket 22a is of greater diameter than the jackets 22 and the pipe coil 23 is disposed within the annular space formed within the jacket 22a. As will be clear from Figs. 2, 3 or 4, the lower ends of the conduits 21 are formed with bell mouths 24 of a diameter suitable to receive the upper ends of adjacent conduits 21, or the upper end of conduit 19. In the places where the sections extend through the floors 25 of the building they are supported by means of brackets 26, welded or otherwise suitably secured to the outside of jackets 22. Thus, most of the sections are independently supported and expansion and contraction thereof due to changes in temperature is made possible by a slight slippage of the conduits 21 within the bell mouths 24.

Adjacent water jackets are connected together by means of one or more conduits 27, each conduit being preferably provided with a valve 28. These conduits are made of a flexible material such as copper in order to permit the aforesaid expansion and contraction of the flue sections.

On the first floor of the building there is shown a cooking stove 30 connected to the flue by means of a conduit 31 passing through the jacket 22a. A damper 32 is located in the flue just below the point of connection of conduit 31.

The upper end of coil 23 is connected to a water supply pipe 33 and the lower end of the coil is connected to a pipe 34 which supplies hot water for use in the building.

The upper end of the uppermost section 20, which terminates within the attic 14, is connected to a double walled conduit 35 which extends through the roof. The space between the walls of this conduit may be filled with any suitable heating insulating material, but a small amount of insulation is sufficient due to the fact that the

flue gases at this point have a comparatively low temperature.

A conduit 36 is connected to the upper part of the uppermost jacket 23 and leads to one or more hot water radiators 37 located in the building. An expansion tank 38 is connected to conduit 36 and is provided with overflow conduit 39 extending through the roof 15. Valves 40 are provided between conduit 36 and the inlets of the radiators 37. Conduit 41 connects the outlets of the radiators with the lower part of the jacket 18 surrounding the furnace. A conduit 42 provided with a valve 43 connects the lower part of conduit 36 with the jacket 22a. The lower end of conduit 36 is connected to return conduit 41 through a valve 44.

The operation of the above described device is as follows:

The products of combustion formed in the furnace 16 pass through the conduit 19 and the conduit 21 of the different sections 20 and 20a and are discharged to the atmosphere through the conduit 35, which extends through the roof. The jacket 18 around the furnace and the jackets 22 and 22a forming part of the flue sections 20 and 20a are filled with water, the valve 28 in the conduits 27 between the jackets being open. This water is thus heated by the flue gases and tends to rise due to the lowering of its specific gravity. The heated water passes through the conduit 36 and through any of the radiators 37 the valves 40 of which are open. From the radiators the water passes through the return conduit 41 to the jacket 18, where it is again heated and ascends through this jacket and through the jackets 20 and 20a. In the event that all of the valves 40 are closed, thermal circulation through the jackets and the conduit 36 may nevertheless take place due to the fact that valve 44 is open, thus connecting conduit 36 with return conduit 41.

The products of combustion produced in stove 30 pass through conduit 31 to the flue. The water passing through the coil 23 is thus heated by the products of combustion from both the furnace and the stove. It will be noted that the water passing through coil 23 flows counter-current to the flue gases within the flue. As previously stated, the water heated in coil 23 constitutes the hot water supply for the building.

In the event that it is not desired to use the furnace, as in the summertime, the valves 28 in the conduit connecting the jacket 22a with the jacket 22 immediately therebelow are closed, as is the valve 44, and the valves 40 of the radiators. If desired, the jackets 18 of the furnace and the jacket 22 immediately thereabove may be drained. Under these conditions, the coil 23 is heated solely by the flue gases discharged from the stove 30. Valve 43 is open and thus thermo circulation may take place upwardly through the jackets 20a and 20 and downwardly through the conduits 36 and 42.

Hence, under all conditions, the conduits 21 which convey the hot flue gases are surrounded by a circulating layer of water which prevents the transmission of excessive amounts of heat to the building. Inasmuch as a circulating layer of water having the same insulating capacity as a masonry chimney is much thinner than the latter, a considerable amount of space in the building is saved.

In the embodiment shown in Figs. 5 through 9 the building is heated directly by air. For this purpose the flue sections 20 and 20a are sur-

rounded by a conduit 50 of suitable material, such as sheet metal or fiber board, forming an annular passage 51 around the jackets 22 and 22a. The upper end of passageway 51 is connected to a space 53 formed between conical plates 54 and 55. Pipes 56 lead from the space 53 and open into the upper parts of the rooms on the second story of the building, preferably in the neighborhood of the windows. A return air duct 57 communicates with the lower parts of these rooms and extends downwardly to an air chamber 58 in heat exchange relationship with the stove or furnace 59. This air chamber is connected to the lower end of the passage 51 surrounding the flue sections. The rooms on the lower floor of the house are heated by air conducted through passages 60, which are branched off from the passage 51, to the upper parts of the rooms. Return ducts 61 lead from the lower parts of these rooms to the chamber 58. A certain percentage of fresh air from outside the building is supplied through the duct 62.

As shown in Fig. 9 the passage 51 may be divided into a plurality of passages by means of partitions 63 whereby the air circulated to and from the different rooms may be kept separate. For this purpose, the chamber 58 which is in heat exchange relation with the furnace or stove 59 may likewise be divided into a plurality of passages by means of partitions 64. As shown in Fig. 6, one of the passages defined by partition 63 may be in communication with the lower part of a room through an opening 65 and with the upper part of the same room by an opening 66, the air heated within the passage rising and passing through the opening 66 into the room, where it is cooled and falls to the lower part of the room and then enters the passage through the opening 65. If desired, fins, corrugations or other means for increasing the surface of the water jackets may be employed, as is shown at 67 in Fig. 9.

As shown in Figs. 6 and 7, a water reservoir 68 is provided in heat exchange relation with the stove or furnace and communicates with the lower end of passage 51, whereupon vapor generated by the heating of the water in reservoir 68 passes into the air flowing through passage 51, thus increasing its humidity, as is desirable in the winter.

As is shown in Fig. 7, the wall of the jacket 20a, within which is located the heating coil 23, may be corrugated. This not only increases the heat transfer area of the jacket, but also tends to create a more or less circular flow of water within the jacket, which improves the heat transfer between the water and the pipe coil.

While we have shown and described two more or less specific embodiments of our invention, it is to be understood that this has been done for purposes of illustration only and is not to be considered as limiting the scope of the invention, which is to be determined by the appended claims.

What we claim is:

1. In a heating system, a furnace, a flue providing a path of flow for hot gas from said furnace, said flue including a plurality of hollow members joined together for direct flow therethrough of gas, an individual liquid jacket surrounding each of said members and said furnace, a conduit connecting adjacent jackets for flow therebetween of liquid, a heating coil disposed in the liquid space of the jacket surrounding one of said members, and conduit means connecting the

uppermost jacket with the lower part of the jacket surrounding said furnace in order to provide for continuous liquid circulation.

2. In a heating system, a furnace, a flue connected to said furnace, said flue including a plurality of sections connected together for serial flow therethrough of gas, an individual liquid jacket surrounding each of said sections, a conduit connecting adjacent jackets for flow of liquid therebetween, a stove connected to said flue, and a heating coil disposed within one of said jackets which is beyond the point of connection of said stove to said flue considered in the direction of gas flow, whereby said coil is heated by the gas discharged from either said furnace or said stove or both.

3. In a heating system, a furnace, a liquid jacket around said furnace, a flue connected to said furnace, said flue including a plurality of sections connected together for serial flow therethrough of gas, an individual liquid jacket surrounding each of said sections, a conduit connecting adjacent jackets, including the jacket around said furnace, for flow of liquid therebetween, a stove connected to a section of said flue above said furnace, and a valve in the conduit connecting the jacket around the section to which said stove is connected with the adjacent lower jacket, whereby the jacket below said stove may be disconnected.

4. In a heating system, a furnace, a liquid jacket around said furnace, a flue connected to said furnace, said flue including a plurality of sections connected together for serial flow therethrough of gas, an individual liquid jacket surrounding each of said sections, a conduit connecting adjacent jackets, including the jacket around said furnace, for flow of liquid therebetween, a stove connected to a section of said flue above said furnace, a heating coil within the jacket around the last-mentioned section, and a valve in the conduit connecting the last-mentioned jacket with the adjacent lower jacket, whereby the jacket below said heating coil may be disconnected when said furnace is inoperative.

5. In a heating system, a furnace, a liquid jacket around said furnace, a flue connected to said furnace, said flue including a plurality of sections connected together for serial flow therethrough of gas, an individual liquid jacket surrounding each of said sections, a conduit connecting adjacent jackets, including the jacket around said furnace, for flow of liquid therebetween, a stove connected to a section of said flue above said furnace, a valve in the conduit connecting the jacket around the last-mentioned section with the adjacent lower jacket, a radiator having an inlet and an outlet, a conduit connecting the jacket around an upper section of said flue with the inlet of said radiator, a return conduit connecting the outlet of said radiator with the jacket around said furnace, and a valved

conduit connecting the conduit leading to said inlet with the jacket around the section to which the stove is connected.

6. In a heating system, means providing a path of flow for hot gas, said means including a plurality of vertically extending hollow members joined together for direct flow therethrough of gas, an individual liquid jacket surrounding each of said members, means for connecting adjacent jackets for flow therebetween of liquid, continuously open conduit means connecting the uppermost jacket with the lower part of the lowermost jacket, and means forming a path of flow around said jackets for air to be heated.

15 7. In a heating system for a multi-room building, a furnace located at the lower part of said building, structure extending through the upper part of said building providing a path of flow for flue gases from said furnace, said structure including a plurality of hollow members joined together for direct flow therethrough of gases, an individual liquid jacket surrounding each of said members, means for connecting adjacent jackets for flow therebetween of liquid and means forming a plurality of paths of flow around said jackets for air to be heated, each of said paths communicating with different rooms in said building.

30 8. In a heating system, a furnace, a flue connected to said furnace, said flue including a plurality of sections connected together for serial flow therethrough of gas, an individual liquid jacket surrounding each of said sections, means for connecting adjacent jackets for flow of liquid therebetween, a radiator, a conduit connecting 35 said radiator with the uppermost of said jackets, a conduit connecting said radiator with the lowermost of said jackets, valve means at said radiator for preventing flow through said radiator, said jackets, conduits and radiator constituting 40 a liquid circulating system, means by-passing said radiator and said valve means for connecting said conduits together to provide for continuous circulation through said system, and a hot water heater in heat exchange relation with said system.

45 9. In a heating system for a building, a furnace, a flue providing a path of flow for hot gas from said furnace, said flue including a plurality of hollow members joined together for direct flow therethrough of gas, an individual liquid jacket surrounding each of said members and said furnace, a conduit connecting adjacent jackets for flow therebetween of liquid, a heating coil disposed in the liquid space of the jacket surrounding one of said members, a conduit means connecting the uppermost jacket with the lower part of the jacket surrounding said furnace in order to provide for continuous liquid circulation, and means for transferring heat from said jackets to 50 the building.
